Primary Examiner — Lakiya Rogers*Assistant Examiner* — Harold E Blackwell, II*(74) Attorney, Agent, or Firm* — Robert C. Kain, Jr.(57) **CLAIM**

I claim the ornamental design for the folding chair arm adjustment bracket and stem, as shown and described.

DESCRIPTION

FIG. 1 is a first side elevational view of the folding chair arm adjustment bracket and stem.

FIG. 2 is a front elevational view of the folding chair arm adjustment bracket and stem.

FIG. 3 is a second side elevational view of the folding chair arm adjustment bracket and stem.

FIG. 4 is a rear view of the folding chair arm adjustment bracket and stem; and,

FIG. 5 is a bottom view of the folding chair arm adjustment bracket and stem.

The top view forming no part of the design.

The broken lines in the FIGS. 1-5 illustrate portions of the folding chair arm adjustment bracket and stem which forms no part of the claimed design.

1 Claim, 5 Drawing Sheets
